UNITED STATES PATENT OFFICE.

CHARLES YOUNG HAILE, OF UNIONTOWN, PENNSYLVANIA.

TROLLEY.

No. 851,415.

Specification of Letters Patent.

Patented April 23, 1907.

Application filed June 26, 1906. Serial No. 323,436.

To all whom it may concern:

Be it known that I, CHARLES YOUNG HAILE, a citizen of the United States of America, residing at Uniontown, in the county of Fayette and State of Pennsylvania, have invented certain new and useful Improvements in Trolleys, of which the following is a specification, reference being had therein to the accompanying drawings.

10 This invention relates to improvements in trolley harps, and has for its object to produce a simply constructed and reliable device whereby the harp portion is prevented from being disassociated in event of the trolley wheel "jumping" the trolley wire.

15 The invention aims to provide a harp similar to the ordinary type of harp carried by the trolley poles of electrically operated cars, and in connection with the trolley-harp, I 20 employ available means for preventing the harp from leaving the conductor or trolley wire in event of the trolley wheel being disconnected from or "jumping" the wire.

25 In constructing my improved harp, I have considered the possibility of interference by wire hangers, crossings, and overhead work that may tend to break and interfere with the positive operation of my improved mechanism, therefore, I have constructed the 30 harp, whereby a portion of the same may recede without breaking or injuring the overhead construction which supports a trolley wire. In this connection, the invention dispenses with the trouble and watchfulness on 35 the part of a car operator heretofore necessitated by the construction of the trolley wheels and harps. To this end, I have devised a trolley-harp having spring-held arms which normally extend above the trolley wire.

40 The detailed construction of my improved harp will be presently described and then specifically pointed out in the claims.

45 Referring to the drawing forming part of this specification, like numerals of reference 45 designate similar parts in the several views, in which:—

50 Figure 1 is a side elevation of my improved trolley harp, Fig. 2 is a plan of the same, Fig. 3 is a vertical sectional view taken on line 55 x—x of Fig. 1, and Fig. 4 is a longitudinal sectional view of a portion of one of the side arms of my improved harp together with one of the yieldable fingers of the same.

55 My improved harp consists of a sleeve 1 adapted to fit upon the end of a trolley pole 2, said sleeve being secured thereon by a pin

3 or similar fastening means. The sleeve 1 carries two parallel arms 4 similar somewhat to any ordinary harp. Between these arms is mounted a transversely disposed pin 5, 60 upon which a trolley wheel 6 is journaled, said wheel having a prolonged hub 7 normally held centrally of the pin 5 by springs 8, secured to the arms 4, as at 9.

65 The ends of the arms 4 are provided with angularly disposed extensions 10 and with sockets 11. In said sockets are loosely mounted the ends of rods 12, said rods being further supported intermediate their ends by springs 14. The springs 14 surround 70 depending pins 15 carried by the rods 12, said pins extending through the extensions 10 and retained therein by cotter pins 16.

75 When the trolley wheel 6 is placed upon a trolley wire 17, the rods 12 extend upwardly 75 at an angle upon each side of said wire, and effectually prevent the lateral displacement of the harp. As the harp passes under cross over wires, or trolley boards, such as are arranged under bridges, the rods 12 recede and are returned to their normal position by the springs 14, which rest upon the extensions 10. The arms 12 are independently arranged and independently supported by their respective rods 15 and springs 14, so 85 that if an obstruction at one side of the trolley only is met with one of the arms only will be depressed, thereby leaving the other arm in position to protect the harp and wheel from lateral displacement. This is an im- 90 portant feature of the invention and adds materially to its efficiency.

95 Since a lateral movement of the trolley wheel 6 is possible by the construction herein shown and described, said wheel can readily adjust itself to a wire that may not be in direct alignment with the pole 2.

100 The entire harp is constructed of strong and durable material especially the rods 12, which will be subjected to considerable wear 100 and tear, by contacting with the wire 17 and its hangers or supports.

105 Such changes in the size, proportion and minor details of construction as are permissible by the appended claims may be resorted to without departing from the spirit and scope of the invention.

What I claim and desire to secure by Letters Patent, is:—

110 1. A trolley harp comprising a sleeve supported upon a trolley pole and with spaced arms extending from the forward end and

provided with longitudinal sockets intermediate the ends of the arms, a trolley wheel mounted for rotation between said arms and between said sockets and the sleeve, spaced 5 rods each seated at one end in one of said sockets and extending at their free ends above the line of the trolley wheel, and yieldable devices between said rods and the free ends of said arms.

10 2. In a device of the class described, a member having means for connection to a trolley pole and spaced longitudinal arms having sockets intermediate their ends and with apertures at their free ends, a trolley

wheel journalled between said arms, rods 15 bearing at one end loosely in said sockets and extending at their free ends above the line of the trolley wheel, pins depending from said rods and extending through the apertures in said spaced arms, and springs operating between said rods and arms and maintaining said rods yieldably in their upward position. 20

In testimony whereof I affix my signature in the presence of two witnesses.

CHARLES YOUNG HAILE.
